[57] CLAIM

The ornamental design for a punch, as shown and described.

DESCRIPTION

FIG. 1 is a perspective view of the punch showing my new design;

FIG. 2 is a top plan view thereof;

FIG. 3 is a bottom plan view thereof;

FIG. 4 is a front elevational view thereof, the rear view being identical;

FIG. 5 is a side elevational view thereof, the opposite side being identical;

FIG. 6 is a perspective view of the punch showing a second embodiment of my new design;

FIG. 7 is a top plan view thereof;

FIG. 8 is a bottom plan view thereof;

FIG. 9 is a front elevational view thereof, the rear view being identical;

FIG. 10 is a side elevational view thereof, the opposite side being identical.

FIG. 1

FIG. 6

FIG. 2

FIG. 7

FIG. 3

FIG. 8

FIG. 4

FIG. 5

FIG. 9
